UNITED STATES PATENT OFFICE

NORMAN H. SAUNDERS, OF HOMEWOOD, ILLINOIS, ASSIGNEE TO RESERVE HOLDING COMPANY, OF KANSAS CITY, MISSOURI, A CORPORATION OF DELAWARE

PARTY-LINE TELEPHONE SYSTEM

Application filed July 2, 1928. Serial No. 289,739.

The present invention relates in general to automatic telephone systems but is more particularly concerned with automatic telephone system of the type which are generally installed in small towns or villages, these systems being commonly known as "mixed service" systems, or "community automatic exchanges"; and the object of the invention, briefly stated, is the provision 10 of new and improved means for signaling the subscribers on rural or party lines.

One of the features of the invention relates to the provision of a common code interrupter for controlling the application of 15 ringing current to the called line.

Another feature of the invention relates to the circuit arrangements by means of which a code selector is arranged so that it will transmit either a one ring or a two ring 20 code, that is, it will transmit either one series or group of ringing current impulses or two separate series or groups of ringing current impulses.

Another feature of the invention relates to 25 the pick-up arrangement for starting the ring and for controlling the changeover from one of the minor switches of the code selector to the other minor switch in order to transmit a two ring code.

Other features relate to the improved connector switches and the improved reverting 30 call switches for use in a system of this type.

These and other features of the invention 35 will be apparent from the following detailed description of the invention.

Referring now to the drawings, comprising Figs. 1 to 5, inclusive, there is shown by means of the usual circuit diagrams sufficient 40 of the apparatus in an automatic telephone system to enable the invention to be readily understood.

In Fig. 1 there is shown at A one of the ordinary common battery automatic sub- 45 stations on a party line.

Each party line has a rotary line switch, such as C, individual thereto. The line switch C is of the well known rotary type with its wipers moving in a forward direc- 50 tion only and having no normal position.

The line switch C has the function of extending the line of sub-station A, when the receiver is removed, to a trunk line terminating in an idle "mixed service" connector, such as indicated by the reference character 55 H.

The connectors, such as H, are of the usual Strowger vertical and rotary type, and have access to individual lines, party lines, trunk lines, and reverting-call 60 switches.

In Fig. 2 is shown a code selector CS which is permanently associated with the connector H shown in Fig. 1. The code selector comprises a number of relays and 65 two minor switches, S and S', which are simple rotary switches adapted to be rotated in response to impulses and restored to normal by the operation of their respective release magnets. Each connector switch 70 has a similar code selector associated therewith.

In Fig. 3 is shown a code interrupter CI which is common to all of the code selectors and connectors in the exchange. The 75 code interrupter comprises a plurality of relays and a 25 position rotary step-by-step sequence switch mechanism. The ratchet and pawl mechanism, as well as the motor magnet of the code interrupter is diagrammatically illustrated in the dotted rectangle of Fig. 3. On the same shaft with the ratchet are five circular cams having spaced notches therein. Associated with each cam there is provided a brush which 80 rides on top of the circular cam and which drops into the spaced notches at certain positions of the interrupter to close its associated contact set. Only the number 5 cam and brush set is illustrated near the top in the dotted rectangle, such cam being in normal position, or the 25th position of the code interrupter. Directly below this illustration, the cam and brush sets, numbers 1 85 to 5, inclusive, are diagrammatically illustrated by the correspondingly numbered brush sets. The numbers to the right of each set indicates the positions of the interrupter switch in which each brush drops

into the spaced notches of its associated cam.

In Fig. 4 is shown one of the reverting call switches to which the connectors, such as H, have access. The reverting call switches comprise a plurality of relays and two minor switches S² and S³, which are similar to the minor switches shown in the code selector. The code interrupter in Fig. 10 3 is also common to the reverting call switches.

In Fig. 4 there is also shown one of the rural lines to which the connectors, such as connectors H, have access. Sub-station A' 15 is one of the local battery magneto sub-stations on the rural line. Associated with each magneto line is an individual repeater, such as R, which comprises a repeating coil and two relays. Each magneto line also 20 terminates in a rotary line switch, such as C', which is similar in all respects to the rotary line switch C shown in Fig. 1.

Fig. 5, shown on the same sheet as Fig. 1, shows the well known method of wiring the 25 connector test bank contacts for trunk hunting connectors. In Fig. 5 only the test contacts of the tenth level accessible to the test wipers of the connector H are shown.

The rural lines are local battery magneto 30 lines and in case a subscriber on a line wishes to call another subscriber on the same line, the calling subscriber will ring, by means of his hand generator, the code of the called subscriber without the necessity of operating 35 the exchange equipment. The common battery party lines, or town lines, are not equipped with magnetos and therefore the reverting call switches, such as the one shown in Fig. 4, are used when a common battery subscriber wishes to call another 40 subscriber on his own line.

The connectors, such as H, are arranged so that they can select an idle trunk line 45 out of a group of trunk lines extending to a distant automatic exchange, but as such connections are not considered a part of this invention no such trunk lines are shown or described.

Having briefly set forth and described the 50 apparatus shown in the drawings, the operation of the system will now be described. For this purpose it will be assumed that the common battery subscriber A desires to call the subscriber A' on the rural line indicated in Fig. 4. Let it be further assumed that the number of the rural line is 55 23 and that the code call for station A' is 54. In this case the calling subscriber must dial the number 2354.

50 When the receiver is removed at the calling sub-station a circuit is completed over the conductors 11 and 12 for the line relay 15 of the line switch C. Upon energizing, relay 15 at armature 20 closes a circuit 65 through the winding of the switching relay

14 and stepping magnet 16 in series, and at its armature 21 connects test wiper 26 to the above circuit at a point midway between the switching relay and the stepping magnet. The operation now depends upon whether the trunk line with which the line switch wipers are associated is busy or idle. If the trunk line is busy there is a ground potential upon the test contact with which the test wiper 26 is in engagement; the switching relay 14 is short circuited, and the stepping magnet 16, which interrupts its own circuit, is operated in the manner of a buzzer to stop the switch wipers to an idle trunk line. Assuming that the connector H is the first idle connector encountered, when the line switch wipers reach this connector the switching relay 14, being no longer short circuited, energizes in series with stepping magnet 16. Stepping magnet 16 is not operated in this circuit on account of the high resistance of the switching relay. Switching relay 14, upon energizing, disconnects the test wiper 26 from the above described test circuit and connects the wiper to its own upper terminal at armature 18, and at its armatures 17 and 19 disconnects the line conductors 11 and 12 from the winding of relay 15 and ground, respectively, and extends them by way of wipers 25 and 27 and bank contacts 28 and 30 to line relay 36 of the connector H. The line relay 36 and the release relay 37 of the connector H are now energized in the usual manner and the latter relay grounds the release trunk conductor extending back to the test contact 29 in order to establish a holding circuit for the switching relay 14 of line switch C. This operation is well understood and need not be explained further.

Release relay 37, upon energizing, at armature 60 grounds the release-trunk conductor 32 as previously described; at armature 62 and its working contact prepares the impulsing circuit and at its resting contact opens a point in the circuit of the release magnet 47; and at armature 61 closes an energizing circuit for the combined changeover and ring cut-off relay 39 as follows: ground by way of armature 61, normally closed off-normal springs 57, and lower winding of relay 39 to battery. Relay 39 upon energizing, at armature 69 prepares a locking circuit for itself and at armature 68 and its working contact prepares the impulsing circuit for the vertical magnet 45.

The calling subscriber may now operate his calling device in accordance with the first digit in the desired number. Each time the line circuit is interrupted by the calling device, line relay 36 falls back and closes the circuit of vertical magnet 45 in series with slow acting series relay 38. The impulsing circuit to the vertical magnet extends by way of grounded armature 52, ar-

mature 59 and its resting contact, armature 62 and its working contact, armature 75, winding of relay 38, armature 68 and its working contact, and winding of vertical magnet 45 to battery. The vertical magnet 5 operates and steps the switch wipers in the well known manner to the desired level. Relay 38 energizes in series with the vertical magnet and at armature 65 and its working contact completes the locking circuit for relay 39 so that the latter relay will not release when its initial energizing circuit is opened by the operation of the off-normal springs 57. In addition to the above, armature 65 10 also closes a circuit for energizing relay 43. This relay, however, preforms no useful function at this time. Soon after the last vertical impulse slow acting relay 38 deenergizes thereby permitting the release of relays 39 and 43. Relay 39, upon deenergizing, at armature 68 and its resting contact prepares the impulsing circuit to the rotary magnet. 15

In response to the dialing of the second digit of the called number, rotary magnet 46 rotates the wipers 95 to 98, inclusive, into engagement with contacts 200 to 203, inclusive. The impulsing circuit through the rotary magnet 46 extends by way of grounded armature 52, impulsing armature 59 and its resting contact, armature 62 and its working contact, armature 75 and its resting contact, winding of slow acting relay 38, armature 68 and its resting contact, armature 86 and its resting contact, and winding of rotary magnet 46 to battery. Slow acting relay 38 is energized in series with the rotary magnet and remains energized during the impulsing period even though relay 41 operates its armature springs 75 as a result of the test wiper 97 encountering grounded contacts. At armature 64 relay 38 maintains the rotary impulsing circuit and at armature 65 again completes the circuit for energizing relay 43. 40

The operation now depends upon whether the called line is busy or idle. If it is busy, ground is present on test contact 201 and busy relay 41, therefore, energizes over the following circuit; from grounded test contact 201, test wiper 97, armature 82 and its working contact, armature 88, and winding of busy relay 41 to battery. 45

When slow acting relay 38 deenergizes after the rotary impulses, said relay at armature 65 opens the circuit of relay 43. Relay 43, however, is slightly slow to deenergize because its upper winding is short circuited by armature 76 and its working contact. Relay 43 deenergizes after an interval and at the normally closed springs controlled by armature 82 completes a locking circuit for busy relay 41 as follows: ground 50 and its resting contact, armature 61, armature 74 and its working contact, normally closed springs 60 controlled by armature 82, armature 88, and winding of busy relay 41 to battery. Busy relay 41, upon energizing, at armature 73 prepares a circuit to the stepping relay 42 which at this time is without effect; at armature 74 and its resting contact opens the circuit of the switching relay 44 and at its working contact closes the previously mentioned locking circuit for the busy relay; at armature 75 opens the impulsing circuit; and at armature 77 connects the busy signaling machine to the lower line conductor. This operation gives the calling subscriber an audible busy signal to inform him that the called line is busy, and therefore he will 70 hear the signal and replace his receiver. 75

It will now be assumed, however, that the called line is idle when the connector H is operated. Under these circumstances as soon as slow acting relay 38 deenergizes, 85 upon completion of the rotary movement, relay 43 deenergizes and completes the following circuit for switching relay 44: from ground by way of armature 61, armature 74 and its resting contact, upper winding of 90 switching relay 44, resting contact of armature 82 and said armature, wiper 97, bank contact 201, conductor 205, switching relay 208 of the called line switch, and through the winding of the stepping magnet 209 to battery. Relays 44 and 208 energize over the above traced circuit and relay 208, upon energizing, removes the line relay bridge at the line switch C' in the well known manner. Switching relay 44, upon energizing, prepares the talking circuit at armatures 83 and 91; at armature 85 prepares a locking circuit for relays 110 and 112 in the code selector CS, Fig. 2; at armature 86 transfers the impulsing circuit from the rotary magnet 46 to the motor magnet 108 of the first minor switch S in the code selector CS; at armature 87 connects guarding ground to test wiper 97 and test contact 201; at armature 88 opens the circuit of busy relay 41; at 100 armature 90 prepared a locking circuit for the ring cut-off of relay 39; and at armature 89 completes a locking circuit for itself which may be traced as follows: ground by way of release trunk conductor 32, armature 105 50 and its resting contact, armature 89, and winding of switching relay 44 to battery. 110

The calling subscriber may now operate his calling device in accordance with the first code digit, or the digit 5. A series of impulses, as before are transmitted over the impulsing circuit by way of armature 86 and its working contact, conductor 103, armature 125, armature 130 and its resting contact, and winding of the motor magnet 108 of minor switch S of the code selector CS to battery. Relays 38 and 43 of the connector H are again operated while the motor magnet 108 of the switch S operates the wipers 115 and 116 into engagement with 125 130

the fifth set of bank contacts. When the slow acting relay 38 deenergizes shortly after the first series of code impulses, a circuit may be traced by-way of armature 65 and its resting contact for energizing relay 112 of the code switch by way of conductor 101 and off-normal springs 117 which are closed as soon as the wipers 115 and 116 are moved off-normal. Relay 112, upon energizing, at armature 126 prepares a circuit for the release magnet 107 of the switch S; at armature 127 prepares a point in the circuit for grounding the interrupter start lead 132; at armature 128 prepares a point in the locking circuit for relay 110; at armature 129 completes a locking circuit for itself; and at armature 130 transfers the impulsing lead 103 from motor magnet 108 of the switch S to motor magnet 106 of the switch S'.

In response to the calling of the last code digit, relays 38 and 43 in the connector H and motor magnet 106 operate. By the operation of motor magnet 106 wiper 113 is moved into engagement with its fourth bank contact. When slow acting relay 38 deenergizes shortly after the last code impulse, a circuit may be traced from grounded armature 65 for energizing relay 111 by way of conductor 101 and off-normal springs 114 of the switch S' which are closed as soon as wiper 113 is moved off-normal. Relay 111, upon energizing, at armature 122 prepares a point in the circuit for release magnet 105 of the switch S'; at armature 123 connects ground to interrupter start conductor 132; at armature 124 connects relay 110 to pick up conductor 134; and at armature 125 opens the impulsing circuit.

As soon as the common interrupter start conductor 132 is grounded relay 207 of the code interrupter is energized over its lower winding. Relay 207, upon energizing, at armature 226 prepares a circuit for grounding the common pick-up conductor 134; at armature 227 closes a locking circuit for itself by way of armature 221; at multiplied armatures 230 grounds the cam and brush sets numbers 1 to 5, inclusive; armature 231 prepares a circuit for connecting common lead 138 to the number 5 cam and brush set; and at armature 228 closes a circuit for energizing interrupter relay 205 in order to start the interrupter mechanism.

Relays 205 and 206 are slow to energize and act as interrupter relays for controlling the operation of motor magnet 208 of the interrupter mechanism. Relay 205, upon energizing, at armature 224 completes a circuit for energizing relay 206. Relay 206 at armature 225 closes a circuit for energizing motor magnet 208. Motor magnet 208, upon energizing, operates its associated armature and pawl mechanism and closes its associated spring contacts 232 near the end

of its armature stroke. By the operation of springs 232 relay 205 is shunted by ground whereupon said relay slowly deenergizes. When relay 205 is fully deenergized the circuit of relay 206 is opened at armature springs 224 and said relay slowly deenergizes due to the short circuit around its winding controlled by armature 224. As soon as relay 206 deenergizes, armature 225 opens the circuit of motor magnet 208 thereby releasing its armature. By the release of its armature motor magnet 208 causes the pawl and ratchet mechanism to move cams numbers 1 to 5, inclusive, from their 25th position, or normal position, to their first position. As soon as springs 232 open, relay 205 again slowly energizes and again completes the circuit for energizing relay 206. Relay 206 again operates the motor magnet 208. This sequence of operation just described continues until ground is removed from the common interrupter start lead 132 and until the code interrupter has been returned to its normal or 25th position.

In position 1 of the code interrupter a circuit may be traced for energizing relay 200 as follows: ground by way of the grounded multiplied armatures 230, number 4 cam and brush set, armature 220 and its resting contact, armature 216 and its resting contact, and winding of relay 200 to battery. Relay 200, upon energizing, at armature 213 grounds the common reverse lead 133 and in addition grounds the common pick-up lead 134 by way of armatures 226 and 215; and at armature 214 prepares a circuit for relay 201 which relay, however, will not energize at this time because of the shunt circuit around it.

When the pick-up lead 134 is grounded, pick-up relay 110 of the code selector energizes and completes a locking circuit for itself by way of armature 121 and armature 128 to the lock ground conductor 104. At armature 119 relay 110 prepares a circuit to the ringing lead 102; and at armature 120 completes a circuit for energizing the reverse relay 109 by way of the grounded reverse lead 133. The reverse relay 109, upon energizing, at armature 118 connects the ringing lead conductor 102 to wiper 115 which, it will be remembered, is in engagement with conductor 139.

In position 2 of the code interrupter ground is removed from the number 4 code interrupter contact whereupon the short circuit around relay 201 is opened and said relay then energizes over the following circuit: ground by way of armature 227, armature 219 and its resting contact, winding of relay 201, armature 214, and winding of relay 200 to battery. Relays 200 and 201 are maintained energized over the above traced circuit. Relay 201, upon energizing, at

armature 215 removes ground from the pick-up conductor 134 thereby preventing any other code selector which may later on be operated from transmitting code ringing impulses at the wrong time. At armature 216 relay 201 opens the original energizing circuit of relay 200 and prepares a circuit for energizing relay 202. When the number 5 cam and brush set is closed in position 2, a ground impulse may be traced by way of armature 230, number 5 brush set, conductor 139, fifth bank contact and wiper 115 of switch S, working contact of armature 118 and said armature, armature 119, and ringing lead 102 to ringing relay 40 and battery in the connector H.

In position 3 of the code interrupter control conductor 233 is again grounded by the number 4 cam and brush set whereupon relay 202 energizes by way of armatures 220 and 216. Relay 202, upon energizing, at armature 217 prepares an energizing circuit for relay 203 but said relay does not energize until ground is removed from the control conductor 233 when the code interrupter reaches position 12. At armature 218 relay 202 connects the common conductor 138 to the number 5 cam and brush set.

The code interrupter continues to operate from this point on in the same manner just described, ground impulses being sent to ringing relay 40 in the connector in positions 2, 4, 5, 8, and 10 of the code interrupter. In positions 3, 5, 7, 9 and 11 the ground circuit to ringing relay 40 is interrupted.

As soon as the code interrupter reaches position 12 ground is removed from the control conductor 233 thereby permitting relay 203 to energize over the following circuit: grounded armature 227, armature 222 and its resting contact, upper winding relay 203, armature 217, and winding of relay 202 to battery. Relays 202 and 203 are maintained energized over the above traced circuit. Relay 203, upon energizing, at armature 219 opens the circuit of relays 200 and 201 whereupon said relays deenergize; at armature 220 and its resting contact opens the initial energizing circuit of relay 200 so that the latter relay will not energize when the control conductor 233 is again grounded; and at armature 220 and its working contacts prepares an energizing circuit for relay 204. Relay 200, upon deenergizing, at armature 213 removes ground from the reverse lead 133 whereupon relay 109 in the code selector deenergizes. Relay 109, upon deenergizing, at armature 118 switches the ringing lead 102 from wiper 115 to wiper 113.

Since wiper 113 is in engagement with the fourth bank contact which is connected to common conductor 138, grounded impulses may be traced in positions 14, 16, 18, and 20 of the code interrupter for operating ring-

ing relay 40 as follows: ground by way of armature 230, number 5 cam and brush set closed in positions 14, 16, 18, 20, and 22, armature 231, armature 218, conductor 138, fourth bank contact and wiper 113 of switch S', resting contact of armature 118 and said armature, armature 119, ringing lead 102, to relay 40 and battery. In position 15, 17, 19 and 21 these grounded impulses are interrupted by the code interrupter.

In positions 21 to 24, inclusive, ground is again connected by the number 4 cam and brush set to control lead 233 whereupon relay 204 energizes by way of armature 220. At armature 223 relay 204 closes a circuit for maintaining relay 203 energized; at armature 222 opens the initial energizing circuit of relay 203 and the circuit of relay 202 whereupon the latter relay deenergizes; and at armature 221 opens the locking circuit of relay 207 which, however, is maintained energized by ground on control lead 233 in positions 21 to 24 of the code interrupter.

Relay 202, upon deenergizing, at armature 218 opens the circuit to the number 5 cam and brush set so that the last ground impulse will not be sent over conductor 138 when the cam reaches position 22. In case, however, wiper 113 was in engagement with the fifth bank contact and conductor 139, a ground impulse would be sent for operating the ringing relay in the connector.

Before the code interrupter reaches position 25, ground is removed by the number 4 cam and brush set from the control lead 233 whereupon relays 207, 204 and then relay 203 deenergize. Relay 207 releases provided ground, in the mean time, has been removed from the interrupter start lead 132. Ground is removed from the interrupter start lead 132 when the called man answers or when the calling party abandons the call in a manner which will be described hereinafter. In case ground has not been removed from the interrupter start lead 132 relay 207 is maintained energized over its lower winding and the code interrupter continues to operate in the same manner as just described.

Returning to the connector in Fig. 1, each time ringing lead 102 is grounded ringing relay 40 energizes. Each time ringing relay 40 energizes a circuit may be traced for energizing relay 214 of the repeater R, Fig. 4, as follows: ground by way of the working contact of armature 71 and said armature, resting contact of armature 66 and said armature, armature 88, wiper 95, bank contact 200, conductor 204, armature 215 and its resting contact, and winding relay 214 to battery. Relay 214, upon energizing, at armature 216 connects ground to the upper talking conductor 218 and also disconnects

the right hand winding of the repeating coil; and at armature 217 disconnects the right windings of repeating coil from conductor 219 at its resting contact and at its working contact connects the lower talking conductor 219 to conductor 206. A circuit may now be traced for ringing the called subscriber as follows: from the ringing machine by way of the working contact of armature 72 and said armature, resting contact of armature 70 and said armature, armature 91, wiper 98, bank contact 203, conductor 206, working contact and armature 217, conductor 219, through all of the ringers on the rural line, conductor 218, and armature 216 and its working contact to ground. Ring-back-tone is transmitted to the calling subscriber in the well known manner each time relay 40 connects the generator to armature 72, the ring-back-tone extending by way of ring-back-condenser RBC and lower talking conductor 31.

When the called party answers during the silent period, or non-ring period, a circuit from ground is closed by way of the normally closed impulse springs on the calling device, through the switch hook springs, and through the two ringer coils in parallel to conductors 218 and 219, and thence by way of armatures 216 and 217, upper and lower right hand windings of the repeating coil, and winding relay 213 to battery, it being understood that relay 214 is energized only during the ringing period. Relay 213, upon energizing, over the above traced circuit, at armature 215 closes a bridge including the left hand windings of the repeating coil across the conductors 204 and 206. Responsive to the closure of this bridge, ring cut-off relay 39 energizes over the following circuit; ground by way of the resting contact of armature 72 and said armature, over the previously traced ringing circuit including at this time the left hand windings of the repeating coil and the armature 215, conductor 204, bank contact 200, wiper 95, armature 83, armature 66 and its resting contact, armature 71 and its resting contact, and through the upper winding of ring-cut-off relay 39 to battery. Ring-cut-off relay 39, upon energizing, at armature 67, and its resting contact disconnects ground from the lock conductor 104 and at its working contact connects ground to release lead 100; at armature 69 completes a locking circuit for itself; and at armatures 66 and 70 connects the upper and lower talking conductors to the switch wipers 95 and 98, respectively; and at the same time opening the ringing circuit. The locking circuit for the ring cut-off-relay 39 may be traced as follows: ground by way of armature 60 and its working contact, armature 50 and its resting contact, working contact of armature 90 and said armature, armature 69, and lower wind-

ing of relay 39 to battery. The talking circuit may be traced over the heavy talking conductors in the usual manner.

When ground is removed from the lock conductor 104 relay 110 in the code selector deenergizes but relay 112 is held energized over its lower winding by way of off-normal springs 117 and conductor 101. When the called party answers and ground is connected to release-lead 100 the release magnets 105 and 107 of the switches S' and S, respectively, energize and restore the switch wipers 113, 115, and 116 to normal position. As soon as the switches S and S' are returned to their normal position the off-normal springs 117 and 114 are opened thereby causing the release of relays 111 and 112. By the release of relays 111 and 112 ground is removed from the interrupter start-lead 132. The code switch CS is now in normal position.

Returning now to the connector the back bridge relay 35 is energized over the bridge loop at the repeater and said relay reverses the current flow extending over conductors 33 and 31 for metering or for supervisory purposes.

When the called subscriber A' replaces his receiver after the conversation, relay 213 deenergizes and opens the bridge circuit at the repeater which in turn causes the back-bridge relay 35 to deenergize. When the calling subscriber A replaces his receiver the line and release relays 36 and 37 deenergize. At armature 60 release relay grounds the release-lead 100 so that the code selector may be released in the manner previously described in case the called man did not answer. At armature 62 release relay closes a circuit for energizing the release magnet 47. By the operation of the release magnet connector H is returned to normal position in the well known manner. By the removal of ground from the release-trunk conductor 32 by armature 60 line switch C is also returned to its normal position. The removal of ground from release-trunk conductor 32 at armature 60 also opens the locking circuits of relays 44 and 39 whereupon said relays deenergize. At armature 61 release relay also disconnects ground from test wiper 97 thereby permitting the called line switch C' to release in the well known manner. All of the apparatus involved in setting up the connection between subscribers A and A' is now in normal position and may be used for extending other calls.

Having described the operation of the apparatus involved in a connection between a common battery subscriber and a rural local battery subscriber, a description will now be given of the operation of the apparatus involved in a connection when a common battery subscriber calls another party on his own line. For this purpose it will

be assumed that sub-station A desires to call a subscriber on his own line. Responsive to the removal of receiver at sub-station A the line switch C operates in the same manner as previously described and again seizes the connector H. Common battery subscribers must dial the digits 0 and 1 before dialing the code ring digits assigned to the wanted subscriber. In this case assuming that the code ring digits are 2 and 3 the calling subscriber will dial the digits 0, 1, 2, and 3.

Responsive to dialing the digit 0 the connector H is operated in the manner previously described opposite the "0" or tenth level. In this case, however, the shaft-controlled springs 92 are operated when the connector wipers are raised opposite the "0" level, or the level in which the trunks to the reverting call switches terminate. Soon after the last vertical impulse, relay 38 de-energizes and permits relay 39 to deenergize and transfer the impulsing circuit from the vertical magnet 45 to the rotary magnet 46.

Since the first four trunk lines in the "0" level are connected to reverting call switches the calling subscriber will dial the digit 1 and the connector will rotate in the same manner as previously described into engagement with the first bank contact in the tenth level or into engagement with the bank contacts terminating the trunk to the first reverting call switch. Assuming that the first reverting call switch is busy, there will be a ground potential on both of the test contacts with which wipers 96 and 97 are in engagement. Accordingly, a circuit will be closed from the grounded test contact by way of wiper 97 and armatures 82 and 88 to the busy relay 41, it being remembered that relay 43 is held energized by the relay 38. Busy relay 41, upon energizing, at armature 74 and its resting contact opens the circuit of the switching relay 44 and at its working contact prepares a locking circuit for itself; at armature 75 opens the impulsing circuit; at armature 76 short circuits the upper winding of relay 43 to render said relay slow to release, and at armature 73 completes an energizing circuit for stepping relay 42 in case test wiper 96 is in engagement with a grounded test contact. The circuit for energizing relay 42 may be traced as follows: from ground by way of the bank contact with which wiper 96 is in engagement, armature 81 and its working contact, armature 63, armature 73, interrupter springs of the rotary magnet 46, and winding stepping relay 42 to battery. At armature 80, relay 42 connects ground to the lower winding of relay 43 in order to maintain said relay in energized position; at armature 79 completes a locking circuit for itself by way of grounded armature 61 and interrupter springs of the rotary magnet; and at armature

78 completes an energizing circuit for the rotary magnet 46 by way of grounded armature 61. The rotary magnet now energizes to rotate the wipers 95 and 98, inclusive, into engagement with the next set of contacts in the same level. Near the end of its stroke rotary magnet 46 opens its interrupter springs thereby interrupting the circuit of the stepping relay 42 whereupon the relay deenergizes. Stepping relay 42, upon deenergizing, opens the circuit of the rotary magnet whereupon the rotary magnet deenergizes. In case the test bank contacts with which the wipers 96 and 97 are now in engagement are grounded the busy relay will be maintained energized and the stepping relay 42 will again energize and operate the rotary magnet to rotate the wipers another step. This cycle of operation continues until the wipers 96 and 97 encounter an idle reverting call switch trunk or until the last set of contacts associated with the last reverting call switch trunk is encountered. In case all of the reverting call switches are busy the connector H will rotate in the manner just described into engagement with the last set of contacts whereupon the busy relay 41 alone is energized, since the test bank contacts 301 and 302, Fig. 5, have no multiple connection. The busy relay then transmits the busy tone to the calling subscriber in the well known manner.

Assuming, however, that the reverting call switch RCS, shown in Fig. 4, is the first idle reverting call switch then when the wipers 96 and 97 encounter the test contacts 302 and 301 there will be no ground potentials thereon and the busy relay 41 will not be energized. Accordingly, when the busy relay 41 is not energized the upper winding of relay 43 is no longer short circuited and said relay quickly falls back and establishes a circuit for the switching relay 44. The circuit for energizing switching relay 44 may be traced as follows: ground by way of armature 61, armature 74 and its resting contact, upper winding switching relay 44, resting contact of armature 82 and said armature, wiper 97, bank contact 301, conductor 305, and through resistance 321 to battery. Switching relay 44, upon energizing, at armature 85 completes a circuit for energizing switching-through relay 34; at armature 86 opens the impulsing circuit to the rotary magnet; at armature 87 connects ground to test contact 301 by way of wiper 97; at armature 88 opens the circuit of the busy relay 41; and at armature 89 completes a locking circuit for itself which extends by way of grounded armature 60 and armature 50. The circuit for energizing switching through relay 34 may be traced as follows: ground by way of armature 67 and its resting contact, armature 85, shaft controlled spring 92 and its working

contact, and winding of relay 34 to battery. Relay 34, upon energizing, at armatures 49 and 53 and their resting contacts disconnects the line relay 36 from the calling line 5 and at their respective working contacts switches the conductors 33 and 31 straight through to the wipers 95 and 98; at armature 50 and its working contact opens the locking circuit of switching relay 44 but 10 said relay does not immediately deenergize because its upper winding is short circuited by ground on the release-trunk conductor 32 and by ground at armature 61; at the working contact of armature 50 connects 15 the two release-trunk conductors 32 and 305 together by way of wiper 97; at armature 51 completes a locking circuit for itself to grounded release-trunk conductor 32; and at armature 52 removes the ground connection 20 thereof so that the connector H will not release at this time. The line and release relays 36 and 37 deenergize in the usual manner but do not cause the release of the switch because in the meantime ground is 25 connected to the release trunk conductors 305 and 32 to maintain relay 34 and lineswitch C in operated position. After an interval 30 switching relay 44 deenergizes. All the relays in the connector H with the exception 35 of switching-through relay 34 are now in deenergized or normal position.

When the switching-through relay 34 of connector H switches the talking conductors straight through, line relay 308 of the reverting call switch ECS, in Fig. 4, energizes 40 over the calling subscriber's loop and causes the energization of release relay 309. Release relay 309, upon energizing, at armature 328 connects ground to the release-trunk conductor 305 thereby maintaining switching through relay 34 and line switch C in operated position. At armature 329 45 relay 309 prepares the impulsing circuit to the motor magnets 317 and 319; and at armature 330 opens the release circuit for the release magnets 318 and 320.

The calling subscriber may now dial the first code digit, or the digit 2. The line relay 308 accordingly sends two impulses 50 for operating motor magnet 317 to cause the switch wipers 346 and 347 to move into engagement with the second set of bank contacts. The circuit for the motor magnet may be traced as follows: ground by way 55 of armature 327 and its resting contact, armature 329, armature 331 and its resting contact, armature 343 and its resting contact, and winding of motor magnet 317 to battery. Slow acting relay 312 is operated in parallel with motor magnet 317 and said relay, upon energizing, at armature 337 removes ground from conductor 360. Shortly after the first series of code impulses, slow acting relay 312 deenergizes 60 and connects ground to conductor 360 there-

by closing an energizing circuit through the upper winding of relay 316 by way of off-normal contact 348. Relay 316, upon energizing, at armature 343 transfers the impulsing circuit from motor magnet 317 70 to motor magnet 319; at armature 344 completes the locking circuit through its lower winding by way of armatures 336 and 330; and at armature 345 prepares release 75 the circuit for release magnet 318 of the switch S².

The calling subscriber will now dial the second code digit, or the digit 3. Accordingly, three impulses are sent over the impulsing circuit for operating motor magnet 80 319 of the switch S³. Motor magnet 319 steps its wiper 349 into engagement with the third bank contact. Slow acting relay 312 is again energized and again removes ground from conductor 360. Shortly after the second series of code impulses have been sent, relay 312 deenergizes and connects ground to conductor 360 thereby completing an energizing circuit for relay 310 by way of off-normal springs 350 of switch S³. Relay 90 310, upon energizing, at armature 331 opens the impulsing circuit at its resting contact and at its working contact prepares a circuit for relay 307; and at armature 332 prepares the release circuit for the release magnet 320. 95

After dialing the last code impulse the calling subscriber will replace his receiver thereby interrupting the circuit of line relay 308 of the reverting call switch. Line relay 308, upon deenergizing, at armature 100 completes a circuit for energizing relay 307 as follows: from ground by way of armature 327 and its resting contact, armature 329, armature 331 and working contact, armature 334, and winding of relay 307 to battery. Relay 307, upon energizing, at armature 323 105 maintains relay 309 in its energized position; at armature 324 connects pick-up relay 314 to the common pick-up lead 134 by way of conductor 134'; at armature 326 grounds the 110 interrupter start lead 132 by way of conductor 132', and at armatures 322 and 325 disconnects the line relay 308 from conductors 304 and 306, respectively, and connects said conductors instead to ground at 115 armature 338 and battery through the upper winding of ring-cut-off relay 311.

Responsive to the grounding of the interrupter start lead 132 relay 207 energizes and initiates the operation of the code interrupter. 120 The code interrupter now operates in the same manner as previously described.

In position 1 relay 200 energizes and connects ground to conductors 133' and 134'. In position 2 relay 201 is energized and in 125 position 3 relay 202 is energized in the manner previously described.

When ground is connected to conductor 134' relay 314 energizes and prepares at 130 armature 339 the ringing circuit of ringing

relay 313. At armature 340 relay 314 closes an energizing circuit for relay 315 whereupon said relay energizes; and at armature 341, relay 314 completes a locking circuit for itself by way of armature 336 and 330. Relay 315, upon energizing, at armature 342 connects ringing relay 313 to wiper 347 of switch S². Since the first code digit was 2 the wiper 347 is in engagement with the second bank contact which is connected to the common conductor 136 which in turn is connected to the number 2 cam and brush set. Accordingly, two long ringing impulses in positions 6-7 and 9-10 are sent to the ringing relay 313. Ringing relay 313, upon energizing, at armature 338 connects generator to conductor 304 from whence it extends by way of bank contact 300, wiper 95, working contact of armature 49 and said armature, conductor 33, wiper 27, armature 19, conductor 11 through all of the subscriber's ringers to conductor 12, armature 17, wiper 25, conductor 31, armature 53 and its working contact, wiper 95, bank contact 303, conductor 306, armature 325 and its working contact, and through the upper winding of ring-cut-off relay 311 to battery.

When the code interrupter reaches position 12 ground is removed from the control lead 233 and relay 203 energizes and opens the circuit of relays 200 and 201. Relay 200, upon releasing, removes ground from conductor 133' whereupon relay 315 deenergizes and at armature 342 transfers the circuit of the ringing relay 313 from wiper 347 to wiper 349 which it will be remembered is in engagement with the third bank contact. Since conductor 137 is connected to the number 3 brush and cam set three ground impulses will be transmitted in positions 14, 16 and 18 for energizing ringing relay 313. Relay 313 again connects generator to the calling line in accordance with the code impulses. The code interrupter continues to operate in the same manner as previously described until the called party answers or until the calling party again removes his receiver. The operation is the same regardless of whether the calling or the called party is the first to remove his receiver. When the called party answers during a silent period, a circuit may be traced from ground by way of armature 338 and its resting contact over the subscriber's loop to battery through the upper winding of ring-cut-off relay 311 whereupon said relay energizes. Relay 311, upon energizing, at armature 333 removes ground from the release-trunk conductor 305 thereby permitting the switching through relay 34 of the connector and line switch C to release; at armature 334 opens the circuit of relay 312; at armature 335 completes a temporary locking circuit for itself; and at armature 336 relay 311 opens

the locking circuit of relay 314 whereupon the latter relay deenergizes. At armature 336 relay 311 also opens the locking circuit of relay 316 but said relay does not deenergize until the off-normal springs 348 open when the wipers 346 and 347 reach their normal position. Relay 307, upon deenergizing, at armature 323 opens the circuit of the release relay 309; at armature 324 opens the initial energizing circuit of relay 314; at armature 326 removes ground from the interrupter start lead 132; and at armatures 322 and 325 disconnects the ring-cut-off relay 311 from trunk conductors 304 and 306 and again substitutes the line relay 308. A short interval thereafter release relay 309 deenergizes and completes the circuit for operating the release magnets 320 and 318 as follows: ground by way of armature 330 and its resting contact, armature 322, and winding of release magnet 320 of switch S³ to battery; and ground by way of armature 330 and its resting contact, armature 345, winding of release magnet 318 to battery. By the operation of the release magnets 318 and 320 switch wipers 346, 347 and 349 are returned to normal position. When said wipers reach normal position off-normal springs 348 and 350 open, thereby opening the circuits of relays 316 and 310 whereupon said relays deenergize. At armatures 345 and 332, respectively, relays 316 and 310 open the circuits to the release magnets 318 and 320. The reverting call switch RCS is now in normal position and may be used for other calls.

When ground was removed from the release-trunk conductor 305, switching through relay 34 of the connector releases and at armature 52 closes a circuit for energizing the release magnet 47 of the connector H as follows: grounded armature 52, armature 59 and its resting contact armature 62 and its resting contact, off-normal springs 58, winding of release magnet 47 to battery. By the operation of release magnet 47 the connector H is returned to its normal position at which time the off-normal springs 58 are opened thereby opening the circuit of release magnet 47. The connector H is now in normal position and may be used for extending other calls.

When ground was removed from release-trunk conductor 305, switching relay 14 of line switch C also releases and line switch C returns to normal position. However, since the called party closes the bridge across the talking conductors 11 and 12, line switch C operates in the same manner as previously described to seize another connector. It will be assumed, in this case, that the line switch C again seizes the connector H and therefore line and release relays 36 and 37 of the connector H again energize. The line relay 36 is used for furnishing

battery to the calling and called subscribers.

Since the bell of the calling subscriber rings at the same time that the bell of the called subscriber does, the calling subscriber will know when the called man has answered by the non-operation of his bell for a certain period of time. The calling subscriber will now take off his receiver and talk with the called subscriber.

When both subscribers hang up, the line and release relays 36 and 37 will release and remove ground from release-trunk conductor 32 thereby permitting the release of the line switch C. All the apparatus is now in normal position and may be used for extending other calls.

Having described the manner in which two ring codes are transmitted, a brief explanation will now be given of the manner in which one ring codes are transmitted. For this purpose we will assume that the connector is again seized and that the calling party, after operating the connector to the line of the desired party and said line is idle, dials the code digit 9. In the same manner as previously described the code switch S moves its wipers 115 and 116 to their respective 9th bank contacts. Now as soon as the series slow acting relay 38 in the connector H deenergizes after the code impulses, a circuit may be traced for energizing relays 111 and 112 as follows: ground by way of armature 65 and its resting contact, conductor 101, off-normal springs 117 to the lower winding of relay 112 and to battery, and over another branch by way of conductor 131, the multiple connected bank contacts, wiper 116, and winding of relay 111 to battery. By the operation of relays 111 and 112 the interrupter start lead 132 is grounded whereupon the code interrupter is started in the same manner as previously described. In position 1 relay 200 is again energized and again connects ground to the pick-up conductor 134 and the reverse conductor 133. The pick-up and reverse relays 110 and 109 are again energized to close the ringing circuit from wiper 115 to ringing conductor 102. In position 2 relay 201 of the code interrupter energizes and locks. In position 3 relay 202 energizes and closes the ringing circuit at armature 218 to the number 5 cam and brush set. In positions 4, 6, 8, and 10 the circuit to the ringing relay 40 of the connector is closed over the following path: from ground by way of the multiple connected armatures 230, number 5 cam and brush set, armature 231, armature 218, common conductor 138, the number 9 bank contact of switch S with which wiper 115 is now in engagement, working contact of armature 118 and said armature, armature 119, ringing lead 102, and winding of ringing relay 40 to battery. Four impulses of ringing current are now sent

out by the ringing relay 40 to signal the desired subscriber. In positions 5, 7, 9 and 11 ground is removed from the ringing lead 102 and the ringing relay therefore interrupts the ringing current. In position 12 relay 203 again energizes and again causes the deenergization of relays 200 and 201. The code interrupter now passes from position 12 to position 25, or normal position, in the same manner as previously described, but in this case without sending any ringing impulses because the switch S' in the code selector CS has not been operated. The code interrupter continues to send out the ringing impulses until the called party answers at which time the release of the code selector and code interrupter is the same as previously described.

It will be seen from the foregoing that although the calling subscriber dialed the number 9 code digit only a one ring code of four rings was transmitted. In a like manner it is obvious from the wiring of the code selector bank contacts of the switch S that one ring codes comprising one ring, two rings, three rings, and five rings may also be transmitted when the code digits dialed are 6, 7, 8 and 10, respectively. It is also obvious that as high as thirty different codes may be transferred, five of which consists of one ring codes from either the code selector or the reverting call switches in combination with the common code interrupter. From the foregoing it is seen that the number four code is taken off of the number 5 cam and brush set. This is because the number 4 cam and brush set is used for controlling relay operations in code selectors and the code interrupter. When the number four code is to be rung the first ring impulse of the number 5 cam is ineffective when the number 4 code is the first ring code of a two ring code because relay 202 of the code interrupter does not close the ringing circuit till after the first ringing position of cam number 5 is passed. In somewhat similar manner the last ring of the number 5 code is ineffective when the number 4 code is the last code ring of a two ring code because relay 202 of the code interrupter falls back in position 21 thereby rendering the last ring impulse from cam number 5 ineffective.

It is also obvious that since the code interrupter of Fig. 3 is a common interrupter it may be used simultaneously by any number of code selectors or reverting call switches. Since relays such as 110 in the code selectors and relays such as 314 in the reverting call switches can only be energized in positions 1 and 2 of the code interrupter there is no danger of the common code interrupter initiating the ringing of a new code in any position other than in position 1 and 2 of the code interrupter.

A brief explanation will now be given of

the manner in which a rural line subscriber such as sub-station A' controls the connectors such as H and code selector such as CS. When the calling subscriber A' removes his receiver a circuit may be traced from ground by way of the impulse springs of the calling device CD through the ringer coils in parallel over conductors 218 and 219 and thence by way of the two right hand windings of the repeating coil through the winding of relay 213 to battery. Relay 213 energizes over the above traced circuit and at armature 215 closes a loop for energizing the line relay 207 of the line switch C'. Line switch C' now energizes in the same manner as described for the line switch C in Fig. 1 and seizes an idle connector, such as the connector H. When the calling subscriber A' dials the digits of the called number the interrupter springs of the calling device CD interrupt the circuit of relay 213 whereupon relay 213 at armature 215 interrupts the loop circuit extending to the seized connector. The connector H and the code selector CS are operated in the same manner as previously described. After the conversation the calling subscriber will replace his receiver thereby interrupting the circuit of relay 213. Relay 213, upon deenergizing, at armature 215 opens the loop circuit thereby permitting the switches to release in the same manner as previously described.

Having described the invention, its utility and operation, what is considered new and is desired to have protected by Letters Patent will be set forth in the appended claims.

What is claimed is:

1. In a code signalling machine, a plurality of cam and brush sets each arranged to transmit a different predetermined number of code impulses, another cam and brush set controlling the starting and stopping of the transmission of the code impulses, means for selecting one of said brush sets over either 40 of two paths, and a relay controlled by said starting and stopping brush set for cancelling one of the code impulses adapted to be transmitted by the selected brush set in case said set has been selected over a particular 45 one of said paths.

2. In a party line telephone system, a plurality of automatic connectors for completing connections to called lines, a code selector individual to each of said connectors 55 for selecting code signals corresponding to desired stations on connected called lines, a code interrupter comprising a plurality of cam and brush sets, means in said code selector for starting the operation of said interrupter, and multiple, connections connecting all the corresponding bank contacts of all the code selectors and corresponding brushes on the interrupter.

3. In a party line telephone system, a plurality of automatic connectors for comple-

ting connections to called lines, a code selector comprising a pair of directly controlled switches associated with each of said connectors for selecting code signals corresponding to desire stations on connected 70 called lines, a plurality of ring back mechanisms accessible to said connectors, each ring back mechanism comprising a pair of directly controlled switches for selecting code signals corresponding to desired stations on 75 the calling line, a code interrupter comprising a plurality of cam and brush sets, and multiple connections connecting all the corresponding bank contacts of all said switches and corresponding brushes on said inter- 80 ruptor.

4. In a code signalling machine, a plurality of cam and brush sets each arranged to transmit a different predetermined number of code impulses, one of said sets selectable over two paths, and means operative in case said one set is selected over one of said paths for cancelling one of the code impulses of the predetermined number.

5. In a telephone system, a line, a plurality of connector switches, a pair of auxiliary switches individual to each of said connector switches, means for establishing a connection with said line by means of any of said connector switches, a code ringing interrupter common to said switches, means for successively and directly operating the pair of auxiliary switches associated with the connector in use to select a particular code ring, a circuit for controlling the operation of said common interrupter, means responsive to the completion of the directive control of said auxiliary switches for closing said circuit to initiate the operation of said interrupter, and local circuits in said 100 interrupter independent of said first circuit for returning said interrupter to normal 105 position.

6. In a telephone system, a line, a plurality of connector switches, a code selector 110 individual to each connector, means for controlling any one of said connectors to establish a connection with said line and for operating the associated code selector to select a particular code ring, a code ringing 115 interrupter common to said switches for transmitting all the code ringing impulses, and means in said associated code selector for initiating the operation of said interrupter to send code ringing impulses corresponding to the position of the operated code selector.

7. In a telephone system, a code ringing machine comprising a plurality of cams having notches indentations therein, a brush for cooperation with each of said cams for closing circuits when said brushes encounter the indentations on said cams, two directly controlled switches successively operated to 125 select two of said brushes, means responsive 130

- to a call for initiating the operation of said machine, a ringing relay when energized for transmitting ringing current, means for energizing said relay a plurality of times, the number of times dependent upon the brush selected by the first operated switch, means controlled by one of said cam and brush sets for transferring the control of said relay to the brush selected by the last operated switch and means for then operating said relay a plurality of times under control of said last selected brush and its associated cam.
8. The combination, with a ringing relay, of a code ringing machine comprising a plurality of cam and brush sets for transmitting a plurality of series of code impulses to said relay, a plurality of progressively movable switches for registering the code ringing digits in a called number, and relays cooperating with one of said cam and brush sets in said machine for placing the transmission of the series of code impulses under control of said register switches successively.
9. In a telephone system, two classes of sub-stations, three digit telephone numbers assigned to the sub-stations of one class, four digit telephone numbers assigned to the sub-stations in the other class, an automatic connector and code selector responsive to the calling of a 3 digit number to call a subscriber in the first class and responsive to the calling of a four digit number to call a subscriber in the second class, and a common ringing equipment automatically started in each case when the calling of the number is completed to selectively signal the wanted sub-station by one ring and two ring codes, respectively.
10. In an automatic telephone system wherein party line subscribers are selectively signalled by code rings, a plurality of connectors having individual code selectors for directively selecting a one ring code or a two ring code dependent upon the number dialled, and a code interrupter common to all said connectors and code selectors for controlling the application of ringing current in accordance with the setting of the code selectors.
11. In an automatic telephone system wherein party line subscribers are selectively signalled by either one or two ring codes, a connector and means for operating said connector into engagement with a called subscriber's line, a first ringing switch associated with said connector for controlling the series of ringing impulses in a one ring code and the first series of ringing impulses in a two ring code, means setting said first switch in accordance with the code digit in a one ring code in case a one ring code digit is dialled or for setting said first switch in accordance with the first code digit of a two
- ring code and the second switch in accordance with the second code digit of a two ring code, a code interrupter common to said connector and switches and other similar connectors and switches, and means controlled by the completion of the setting of both said switches in case two code digits are dialled or by the completion of the setting of said first switch in case a one ring code digit is dialled for initiating the operation of said common interrupter.
12. In a telephone system, a party line connector having primary and secondary magnets, two auxiliary ringing current selecting switches individual to said connector, each ringing switch having a motor magnet, a line relay and a series relay in said connector, an impulsing circuit to each of said magnets controlled by said line relay, said series relay included in said impulsing circuits, contacts on said series relay for causing said magnets to be successively controlled by said line relay, and means including off-normal springs on the first of said ringing switches in series with said contacts for causing the impulsing circuit to be transferred from the magnet of the first ringing switch to the magnet of the second ringing switch.
13. In an automatic telephone system wherein party line subscribers are selectively signalled by two series of code rings, a reverting call switch comprising two ringing switches for enabling calling subscribers to call other subscribers on their own line, means for seizing said reverting call switch and for operating both said ringing switches to select a two ring code, and a code interrupter common to said switches and similar switches for controlling the transmission of the two series of ringing impulses in accordance with the setting of the ringing switches.
14. In an automatic telephone system wherein party line subscribers are selectively signalled by two series of code rings, a reverting call switch comprising two ringing switches for enabling calling subscribers to call other subscribers on their own line, means for seizing said reverting call switch and for operating both said ringing switches to select a two ring code, a code interrupter common to said switches and similar switches for controlling the transmission of the two series of ringing impulses in accordance with the setting of the ringing switches, a ringing circuit over which said ringing impulses are transmitted, and means controlled by said interrupter for transferring the ringing circuit from the first ringing switch to the second ringing switch after the transmission of the first series of ringing impulses.
15. In an automatic telephone system wherein party line subscribers are selectively signalled by two series of code rings, a re-

- verting call switch comprising two ringing switches for enabling calling subscribers to call other subscribers on their own line, means for seizing said reverting call switch and for operating both said ringing switches 5 to select a two ring code, a code interrupter common to said switches and similar switches for controlling the transmission of the two series of ringing impulses in accordance with the setting of the ringing switches, a ringing circuit over which said ringing impulses are transmitted, and means controlled by said interrupter for transferring said ringing circuit from the first ringing switch to the second ringing switch after the transmission of 10 the first series of ringing impulses and for transferring the ringing circuit from the second ringing switch back to the first ringing switch after the transmission of the second series of ringing impulses in order to repeat 15 the first series of ringing impulses.
16. In a telephone system wherein party line subscribers are selectively signalled by two series of code rings, two ringing switches, means for operating said switches to select a two ring code, a ringing relay for connecting ringing current to the called party line, a circuit over which code impulses are sent for operating said relay, and 20 means for transferring said circuit from the first switch to the second switch after the transmission of the first series of code rings in order to control said relay to transmit the second series of code rings.
- 35 17. In a telephone system wherein party line subscribers are selectively signalled by two series of code rings, a reverting call switch comprising two ringing switches for enabling calling subscribers to call back on their own line, means for seizing said reverting call switch, means for operating said ringing switches to select a two ring code, and means for transmitting two series of ringing impulses in accordance with the setting of said ringing switches.
- 45 18. In an automatic telephone system wherein party line subscribers are selectively signalled by either one or two ring codes, a reverting call switch comprising two ringing switches, means for seizing said reverting call switch and for operating both said ringing switches to select a two ring code in case a two ring code is called or for operating only the first of said ringing switches 50 to select a one ring code in case a one ring code is called, and a code interrupter common to said switches and similar switches for controlling the transmission of the series of ringing impulses in accordance with the setting of the ringing switches.
- 60 19. In an automatic telephone system wherein party line subscribers are selectively signalled by either one or two ring codes, a reverting call switch comprising two ringing switches, means for seizing said revert-
- ing call switch and for operating both said ringing switches to select a two ring code in case a two ring code is called or for operating only the first of said ringing switches to select a one ring code in case a one ring code is called, a code interrupter common to said switches and similar switch for controlling the transmission of the series of ringing impulses in accordance with the setting of the ringing switches, and means for initiating the operation of said interrupter responsive to the setting of both ringing switches in case a two ring code is called and responsive to the setting of the first ringing switch only in case a one ring code is called.
20. In combination, an interrupter mechanism comprising a plurality of cam and brush sets, a switch equipped with two sets of wipers adapted to be positioned for selecting said sets, and a starting circuit for said mechanism controlled by a single wiper in certain position and by the two wipers jointly in said other positions.
- 25 21. In combination, an interrupter mechanism comprising a plurality of cam and brush sets, a switch equipped with two sets of wipers adapted to be positioned for selecting various pairs of said sets, a signal circuit for said switch, and a relay controlled by said mechanism for connecting said two wipers alternately to said signal circuits.
- 30 22. In a telephone system, a party line connector having primary and secondary motor magnets, two auxiliary ringing current selecting switches individual to said connector, a motor magnet for each ringing switch, a line relay in the connector for controlling the primary and secondary magnets thereof to extend a connection to a line, and a switching relay in the connector for placing the motor magnets of said ringing switches under the control of said line relay when a connection is extended to an idle line.
- 35 23. In a telephone system, a party line connector, a line relay in the connector for controlling the operation thereof to extend a connection to a called line, a switching relay in the connector energized when a connection is established with an idle line, a first code selecting switch placed under the control of said line relay responsive to the operation of said switching relay, and a second code selecting switch placed under the control of said line relay responsive to the operation of said first switch.
- 40 24. In a telephone system, a party line connector, a line relay in the connector for controlling the operation thereof to extend a connection to a called line, means for testing the line connected with for its busy or idle condition, two code selecting switches

individual to said connectors, and means responsive when the line connected with is idle for successively placing said switches under the control of said line relay.

5 In witness whereof, I hereunto subscribe my name this 28th day of June, A. D. 1928.

NORMAN H. SAUNDERS.
